(57) **CLAIM**

The ornamental design for a telescopic plant light, as shown and described.

DESCRIPTION

FIG. 1 is a perspective view of a telescopic plant light showing my present design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate portions of the telescopic plant light which form no part of the claimed design.

The drawings contain symbolic break lines in FIG. 1-7. The portion between the break lines forms no part of the claimed design.
